UNITED STATES PATENT OFFICE

WILLIAM F. GRUPE, OF LYNDHURST, NEW JERSEY, ASSIGNOR TO BOUCHER CORK CO., INC., OF NEW YORK, N. Y., A CORPORATION OF NEW YORK.

CIGARETTE SLIDE CONTAINER

Application filed May 9, 1928. Serial No. 276,247.

This invention relates to improved packages or containers for cigarettes.

Pursuant to my invention, the package for cigarettes and the like embodies an outer element in the form of a pouch and an inner element in the form of a slide for enclosing the cigarette.

The elements of the various embodiments of my invention are preferably assembled to conform to the practice of present-day types of filling and packaging machines.

Pursuant to one preferred form of my invention, the outer element is of the pouch formation and may constitute the label, i. e., bearing the name and trademark of the cigarette, the name and address of the manufacturer and other desirable advertising indicia. Such pouch is advantageously open at one end only, through which open end the slide element containing the cigarettes is inserted. The cigarettes are preferably enclosed in suitable wrapping material, such as metal foil, glassine paper, etc., which is applied either directly about the cigarettes or about the slide containing the cigarettes.

The open end of the pouch and the upper end of the slide may be sealed by a strip of adhesively coated paper or other suitable mechanical sealing medium; where revenue stamps are required, the stamp may serve as the sealing medium.

In other preferred forms of my invention, the pouch material may be transparent, such as of glassine, or paraffined or waxed paper and the like, and the advertising indicia are printed on the exposed portions of the slide element, and accordingly visible through the transparent pouch material.

I prefer tin foil for wrapping the cigarettes directly or for enwrapping the slide containing the cigarettes.

Among the advantages gained by my invention in the several forms thereof, are increased stiffness imparted to the package in its original status and after being opened the cigarettes withdrawn, thereby positively protecting the enclosed cigarettes from external pressure with attendant loss of tobacco filler, improved sanitary condition of cigarettes; low cost of material employed; low cost of

assembly and packaging; improved manner of accessibility to cigarettes when initially opened and in subsequent use; effective sealing of the cigarettes against losses of aroma and in moisture content; and greatly enhanced appearance of the package in original and subsequent status.

Further features of my invention will be more fully understood from the following detail description of the accompanying drawings.

Fig. 1 is a perspective view of one embodiment of my invention, showing the container open and the slide partially withdrawn; Fig. 2 is a top plan view of the embodiment shown in Fig. 1, when in original condition, and Fig. 3 is a sectional elevation on the line 3—3, Fig. 1. It will be observed that the cigarettes as illustrated in this embodiment, are directly enwrapped with tin foil and enclosed in the slide.

Fig. 4 is a detail perspective view of a preferred form of slide element.

Fig. 5 is a perspective view of cigarettes enclosed in the slide element of Fig. 4; Fig. 6 is a perspective view of the slide and the contained cigarettes enclosed in the tin foil; Fig. 7 is a perspective view of a modified form of my package formed by enclosing the parts of Fig. 6 in a pouch; this embodiment also illustrates the use of a revenue stamp or a mechanical sealing medium; and Fig. 8 is a sectional elevation on line 8—8, of Fig. 7.

Fig. 9 illustrates a further modification, showing the use of a pouch of transparent material; Fig. 10 illustrates my package embodying transparent pouch material and the slide containing the cigarette with tin foil enwrapped about the slide; and Fig. 11 is a perspective view of another preferred form of slide.

Referring to Figs. 1 to 4, inclusive, this embodiment of my invention comprises the outer element in the form of a pouch 10 of standard or other approved blank and fold formation, and preferably having an open top end 11. It is desirable to provide the thumb opening 12 at the center of the upper edge 11 at the front side of the pouch, to facilitate manual gripping of the slide element of 100

the package to gain access to the enclosed cigarettes, as will appear more fully hereinafter. Such pouch may be of any suitable stock of paper or other suitable material.

5 The trade name and symbol of the cigarette, the name and address of the manufacturer and other desired advertising matter may be applied on the exposed faces of the pouch material, as is indicated at 13 conforming to the prevailing practice on present day 10 types of cigarette packages.

15 The cigarettes 14 are positioned within the slide 15, which in the original package is enclosed within the pouch 10. The open end of the package in original condition may be mechanically sealed by any suitable means. Where revenue stamps are required, the revenue stamp 16 may be applied at its adhesive face to span from the upper edge of the rear 20 face of the pouch, thence across the upper end or flap of the slide 15 and thence to the upper edge of the front face of the pouch; such mechanical seal preferably conceals the thumb opening 12.

25 One preferred form of slide is indicated in Fig. 4; it is preferably formed of cardboard or like relatively stiff stock of paper or other suitable material and is blanked or otherwise formed to comprise, in addition to 30 the upper end or flap 15^a as aforesaid, the tray bottom portion 15^b, the opposite tray sides 15^c, and the lower end or flap 15^d. The upper and lower flaps or ends 15^c, 15^d are 35 preferably scored as indicated at 15^e respectively, and the extreme flap portion 15^a at the upper end is preferably pointed, as indicated in Fig. 4, to facilitate insertion.

40 Preferably, the cigarettes are enclosed within a suitable air and moisture proof material, such as tin foil, waxed or paraffin paper, and the like. As is indicated in Figs. 1 and 3, such protective wrapping material 17 may be directly applied to the cigarettes 14, as by enwrapping the same by overlapping 45 or equivalent formation. The wrapped cigarettes 14 are then enclosed within the slide 15, and the same enclosed within the pouch 10, after which the revenue stamp 16 or other mechanical sealing medium is applied to the open end of the pouch and about 50 the upper end of the slide 15.

55 When such original package is desired to be opened the revenue stamp is grasped and pulled, thereby tearing the stamp and particularly between the flap 15^a of the slide 15 and the front side of the pouch 10, and preferably to expose the thumb opening 12, then the slide 15 is grasped and pulled, removing, if not previously removed, the portion of the 60 revenue stamp connecting the slide with the rear face of the pouch, whereupon the flap 15^a of the slide is opened out and a sufficient portion of the tin foil opened or torn and removed to permit access to the cigarettes.

65 In Figs. 7 and 8, I have illustrated another

form of package in original condition, embodying my invention. In this embodiment, the tin foil 17^a is enwrapped about the slide 15 containing the cigarettes, and thus enclosed within the pouch material 10. Otherwise, 70 the package illustrated in Figs. 7 and 8, excepting as noted hereinafter, comprises parts substantially corresponding to parts appearing in the modification illustrated in Figs. 1 and 3; like reference numbers designate like 75 parts.

75 To form the package illustrated in Figs. 7 and 8, the cigarettes 14 are first enclosed within the slide 15, as is indicated in Fig. 5, and thereupon the tin foil 17^a or equivalent 80 enwrapped about the slide 15 and contained cigarettes 14, as is illustrated in Fig. 6; then the resulting assembly is inserted within the pouch material 10. A revenue stamp 16 or other mechanical sealing medium may be applied to and about the upper end of the pouch 85 and intervening parts.

85 In this instance, the adhesive face of the revenue stamp 16 becomes attached at one end 16^a to the upper edge portion of the rear 90 face of the pouch material; at its intermediate portion the stamp adheres to the upper end folds of the tin foil 17^a or equivalent, and the opposite end portion 16^a of the stamp is attached to the front face of the pouch material, preferably concealing the thumb opening 12. When such package in its original condition is opened, the intermediate portion 95 of the revenue stamp 16 or equivalent is grasped, thereby tearing away a portion 100 thereof together with adhered parts of the upper folded end of the tin foil 17^a, thus severing the slide and tin foil 17^a from the material of the pouch; thereupon the thumb is placed within the thumb opening 12, to facilitate the withdrawal of the slide 15 and the 105 therein contained cigarettes 14.

110 In Figs. 9 and 10 I illustrate further embodiments of my invention, primarily showing the use of a pouch 20 of transparent or 110 substantially transparent material such as glassine paper, waxed or paraffined paper or other suitable stock. Preferably glassine paper coated only on its inner face is employed, thereby rendering the pouch material water and moisture proof, and locating the wax to prevent rubbing off upon the clothes or the fingers of the user. Such wax-coated paper adds a degree of stiffness to the 115 pouch material.

120 Such pouch 20 is preferably of open-ended formation, similarly as hereinabove, and also preferably includes a thumb opening 12^a; a revenue stamp 16 or other mechanical sealing medium may be employed to bridge and mechanically close the open-end of the pouch 20, similarly as aforesaid. In the modification illustrated in Fig. 9, the cigarettes may or may not be enclosed within tin foil 17, 125 similarly as hereinabove; when tin foil is 130

employed, it may enclose the slide 15 containing the cigarettes 14, similarly as in Figs. 1 and 3, or may be enwrapped directly about the cigarettes, similarly as in Fig. 7.

Fig. 10 corresponds largely to the modification shown in Fig. 9, and illustrates the tinfoil 17 or equivalent directly enclosing the cigarettes 14, and placed within the slide 15; the resulting assembly is enclosed within the pouch 20 of transparent material.

The manner of removal of material and of access to the enclosed cigarettes in the embodiments illustrated in Figs. 9 and 10 correspond substantially to the modifications illustrated in Figs. 1 and 7 respectively.

When transparent pouch material is used, the exposed faces of the slide may bear the trade mark and other advertising indicia of the brand of cigarettes enclosed.

From the above it will be apparent, that my improved forms of package afford access to the cigarettes without requiring the cigarettes to be "knocked out," as is required with present day forms of pouch containers. Such "knocking-out" operation entails inconvenience and also results in loosening the tobacco filling of the cigarettes, causing detriment to the appearance and smoking qualities of the cigarettes.

By the use of a slide, the contained cigarettes may be readily withdrawn partially from the pouch after the original package box has been opened as above stated, to enable the upper flap of the pouch to be opened, thus preserving the appearance and filler content of the cigarettes. Upon the removal of the desired cigarettes, the upper flap of the slide is folded back to its closed position and the slide returned within the pouch. The relatively stiff material of the slide imparts rigidity to the package as a whole, and protects the enclosed cigarettes from exterior pressure. Such action is enhanced by the folded closed positions of the upper and lower ends or flaps of the slide.

Preferably, the tray sides 15° are scored or indicated at 15°, see Fig. 11, thereby biasing the free end portions of these sides 15° to fold more and more over the enclosed cigarettes as the number of enclosed cigarettes is decreased. Such increased protective action accrues by reason of the usual manual handling of a partially depleted package and by the exterior pressure attending the placing and carriage of the package within a garment pocket or the like, as appears in Fig. 8.

In the various embodiments of my invention inexpensive materials are employed, and the manner of the arrangement of the elements of my package enables the cigarettes to be packaged and sealed pursuant to accepted practice and by present day filling, weighing and wrapping machines.

By the use of tinfoil or the like, the aroma and moisture content are effectually pre-

served. The tinfoil layer serves also to stiffen the package material, and is effective in the original and depleted status of the package.

All of the aforesaid structural improvements of my package are effective in preserving the appearance and the filler content of the cigarettes, and afford full scope of display of advertisement upon the package.

I claim:

1. A container for cigarettes comprising an outer pouch element, an inner slide element, said slide element being arranged to receive and contain cigarettes, and an element of readily rupturable material wholly enclosing said inner slide element.

2. A container for cigarettes comprising an outer pouch element having an open end, an inner slide element adapted to contain cigarettes disposed within said pouch element, said inner slide element being provided with a flap portion normally positioned within said outer pouch element, an element of readily rupturable material wholly enclosing said inner slide element, and mechanical means for jointly sealing said slide element and said pouch element at said open end.

3. A container for cigarettes comprising an outer pouch element, a slide element disposed within said pouch element for containing cigarettes, said slide element including a flap end portion normally positioned at one end of the package, and an element of readily rupturable material wholly enclosing said inner slide element.

4. A container for cigarettes comprising an outer pouch element having a single open end, an element disposed within said pouch element for containing cigarettes, said element including a closure flap portion normally disposed at said open end, an element of readily rupturable material wholly enclosing said inner slide element, and mechanical means for jointly sealing said pouch element and said inner element at said open end.

5. A container for cigarettes and the like comprising an inner slide member adapted to receive and contain cigarettes, an outer member having a single opening at a certain side, an element of readily rupturable material wholly enclosing said inner slide member, and mechanical means for jointly sealing said slide member and said outer member at said certain side.

6. A container for cigarettes and the like comprising an inner slide member adapted to receive and contain cigarettes, an outer member having a single opening at a certain side, said slide member having a movable flap at said certain side, an element of readily rupturable material wholly enclosing said inner slide member, and mechanical means for jointly sealing said slide member and said outer member at said certain side.

7. A container for cigarettes and the like comprising an inner slide member adapted

- to receive and contain cigarettes, an outer member having a single opening at a certain side, said slide member having a movable flap at said certain side, said slide member having a movable flap at its side opposite to said certain side, an element of readily rupturable material wholly enclosing said inner slide member, and mechanical means for jointly sealing said slide member and said outer member at said certain side. 10
8. A container for cigarettes comprising an outer pouch member, an inner slide member, said slide member being arranged to receive and contain cigarettes, said slide member having lateral sides tending to tilt inwardly, and an element of readily rupturable material wholly enclosing said inner slide member. 15
9. A container for cigarettes comprising an outer pouch member, an inner slide member, said slide member being arranged to receive and contain cigarettes, said slide member having one of its opposite lateral sides scored to tend to tilt it inwardly, and an element of readily rupturable material wholly enclosing said inner slide member. 20
10. A container for cigarettes comprising an outer pouch member, an inner slide member, said slide member being arranged to receive and contain cigarettes, said slide member having its opposite lateral sides scored to tend to tilt the same inwardly, and an element of readily rupturable material wholly enclosing said inner slide member. 25
11. A container for cigarettes comprising an outer pouch element, an inner slide element, said slide element being arranged to receive and contain cigarettes, the material of said pouch element being moisture resistant, and an element of readily rupturable material wholly enclosing said inner slide element. 30
12. A container for cigarettes comprising an outer pouch element, an inner slide element, said slide element being arranged to receive and contain cigarettes, the material of said pouch member being formed of paper stock bearing a moisture resistant medium, and an element of readily rupturable material wholly enclosing said inner slide element. 35
13. A container for cigarettes comprising an outer pouch element, an inner slide element, said slide element being arranged to receive and contain cigarettes, the material of said pouch member being formed of paper stock bearing a moisture resistant medium on its inner face, and an element of readily rupturable material wholly enclosing said inner slide element. 40
14. A container for cigarettes comprising an outer pouch element, an inner slide element, said slide element being arranged to receive and contain cigarettes, the material of said outer pouch element being transparent and moisture resistant, and an element 45
- of readily rupturable material wholly enclosing said inner slide element. 50
15. A container for cigarettes comprising an outer pouch element, an inner slide element, said slide element being arranged to receive and contain cigarettes, the material of said outer pouch element being of transparent paper stock bearing a moisture resistant medium, and an element of readily rupturable material wholly enclosing said inner 55
- slide element. 70
16. A container for cigarettes comprising an outer pouch element, an inner slide element, said slide element being arranged to receive and contain cigarettes, the material of said outer pouch element being of transparent paper stock bearing a moisture resistant medium on its inner face, and an element of readily rupturable material wholly enclosing said inner 60
- slide element. 75
- In testimony whereof I have signed this specification this 5th day of May, 1928.
